UNITED STATES PATENT OFFICE.

WALTER BUSWELL, OF PHILADELPHIA, PENNSYLVANIA, ASSIGNOR TO STOKES & SMITH COMPANY, OF PHILADELPHIA, PENNSYLVANIA, A CORPORATION OF PENNSYLVANIA.

BOX-COVERING BLANK.

1,343,193.

Specification of Letters Patent. Patented June 15, 1920.

Application filed October 2, 1917. Serial No. 194,323.

To all whom it may concern:

Be it known that I, WALTER BUSWELL, a citizen of the United States, residing at Germantown, Philadelphia, in the county 5 of Philadelphia, and State of Pennsylvania, have invented new and useful Improvements in Box-Covering Blanks, of which the following is a specification.

The present invention relates to certain 10 novel and useful improvements in box covering blanks of the character shown and described in the Patent No. 845,205, dated February 26, 1907, granted to J. S. Stokes.

The box covering blank forming the subject matter of said earlier patent embodies 15 a sheet of thin, flexible material having integral side wings provided with end lap projections adapted to be folded around the box corners, and small corner staying tabs 20 consisting of separate pieces of staying material attached to each wing and its extensions and positioned thereon over the corner folding lines to set the corner joints of the box shell, the blank itself when applied to 25 the shell completely covering the bottom and side walls thereof. This style of box covering blank may be used to great advantage under ordinary conditions for covering and staying box shells, but under 30 certain special conditions difficulty may be encountered in successfully employing such blank. For instance, in covering an extremely narrow box with such a blank, particularly where a box covering machine is 35 employed for applying the blank, it is difficult to put the two pairs of oppositely arranged staying tabs on the blank body, because the width of the blank is not sufficient to allow the machine to operate successfully 40 in applying the transversely opposing tabs. Furthermore, such earlier box covering blank requires the application of four separate tabs, one for each corner, these tabs being relatively small, and in some respects, 45 difficult to place, and in addition, no provision is made in such blank for reinforcing or staying the folding line or crease extending between transversely opposing tabs.

In the present instance I propose to ob- 50 viate the disadvantages incident to such a blank by employing but two relatively long staying strips in the place of four separate tabs, thereby permitting the ready applica- 55 tion of the same by the box covering ma-

chine, these stay strips overlying certain 55 folding lines of the blank body so as to not only stay the joints of the box shell, but also to reinforce the transverse edges of the covered shell.

It is also my purpose to provide a stayed 60 box covering blank which will embody the desired features of simplicity and efficiency and which may be produced quickly and economically and applied to the box shell in such manner as to not only strengthen the 65 corners of the latter but also to strengthen the ends thereof.

With the above recited objects and others of a similar nature in view, my invention 70 consists in the construction, combination and arrangement of parts set forth in and falling within the scope of the appended claims.

In the accompanying drawings:

Figure 1 is a perspective view of one form 75 of box blank embodying my invention and having the stay strips applied thereto.

Fig. 2 is a perspective view of one of the stay strips adapted to be pasted to the body of the blank.

Fig. 3 is a perspective view of a box 80 shell with my improved cover blank partially applied thereto.

Fig. 4 is a sectional view taken on the line 4-4 of Fig. 1.

Fig. 5 is a vertical longitudinal sectional 85 view taken through one end of the partially covered box on the line 5-5 of Fig. 3.

Fig. 6 is a similar view taken on the line 6-6 of Fig. 3.

Referring now to the accompanying draw- 90 ings in detail the numeral 1 indicates the body portion of the blank which is shaped to correspond to the size and shape of the top or bottom of the box to be covered. This body portion is provided with end 95 flaps or wings 2 and side flaps or wings 3. The stay strip employed in the present instance is indicated by the numeral 5 and is in the nature of a relatively long strip of strong or tough but flexible material, such 100 as manila paper, muslin or any other suitable flexible material, and two of these strips are employed, each having one face thereof completely covered or coated with an adhesive 6 so that in applying the strip 105 the adhesive face thereof is placed in contact with the blank body and sealed or pasted thereto, as shown in Fig. 1. In the

application of the strips to the blank body they are placed transversely of the latter and adjacent the end of the body so as to overlie the transverse folding lines 7 of the 5 blank. After the strips have been applied to the blank, both the strips and the blank may be notched as shown at 8 to form the usual end laps 9 on the side flaps or wings 3, these end laps being reinforced by the corner 10 tab sections 10 of the staying strip 5, and which sections are of course formed in the notching operation. In the operation of applying this cover blank to the box shell, the uppermost face of the blank, or that on 15 which the stay strips are pasted is coated throughout with an adhesive. The top or bottom of the box shell, as the case may be, is then centered upon the body portion 1 of the blank and the side and end wings 3 of 20 the latter are then folded up and applied to the side and end walls of the box either by a machine or by hand, accordingly as the box is machine or hand covered. The free, 25 marginal edge portions of the side and end wings may of course be folded in against the inner faces of the walls of the box shell, as will be readily understood by reference to Fig. 5. It will be noted that in the application of the cover blank to the box shell 30 the former will be folded along the transverse folding lines 7 so that the crease or fold will run centrally and longitudinally of the stay strips, thereby causing both the transverse ends or edges and the corners of 35 the box shell to be thoroughly protected and reinforced, and naturally these strips also strengthen or reinforce the cover blank itself at the points where it is subjected to the greatest amount of wear and tear when applied to the box, that is along the corners and edges.

While I have herein shown and described one particular embodiment of my invention, I wish it to be understood that I do not 45 confine myself to all the precise details of construction herein set forth by way of illustration, as modification and variation may be made without departing from the spirit

of the invention or exceeding the scope of the appended claims.

50

What I claim is:

1. As a new article of manufacture, a box covering and staying blank comprising a body portion having integral side and end wings, and end laps at opposite ends of the 55 said side wings and adapted to be folded about the box corners, and notched staying strips of reinforcing material arranged transversely of the blank adjacent opposite ends thereof and extending throughout the 60 major portion of the width of the blank and overlying transverse folding lines of the blank whereby to reinforce the vertical corners and the transverse end edges of a box to which the blank is applied.

65

2. As a new article of manufacture, a box shell covering and staying blank comprising a body portion having integral side and end wings, said side wings being notched at opposite ends to provide end laps at such ends 70 of the side wings, which laps are adapted to be folded about the box corners, and a pair of staying strips of reinforcing material adhesively attached to the upper face of the blank and extending transversely of the 75 blank adjacent opposite ends thereof and overlying transverse folding lines of the blank, said staying strips having notches coinciding with the notches of the side wings to provide end tab sections reinforcing the corner joints of the box shell, the intermediate sections of the reinforcing strips reinforcing the end edges of the box shell.

80

3. As a new article of manufacture, a box 85 shell covering and staying blank having adhesively attached to one face thereof a reinforcing strip having end sections adapted to constitute staying tabs for opposite corners of a box shell and an intermediate section 90 adapted to constitute a reinforcement for the edge of the shell extending between the corners stayed by the tabs.

In testimony whereof I have hereunto set my hand.

WALTER BUSWELL
